UNITED STATES PATENT OFFICE.

ROBERT F. LINDEMANN, OF PROVIDENCE, RHODE ISLAND, ASSIGNOR TO ALFRED VESTER SONS, INC., OF PROVIDENCE, RHODE ISLAND, A CORPORATION OF RHODE ISLAND.

DESIGN FOR A HUSK FOR LIGHTING FIXTURES.

60,463.

Specification for Design.

Patented Feb. 21, 1922.

Application filed July 28, 1921. Serial No. 488,245. Term of patent 7 years.

To all whom it may concern:

Be it known that I, ROBERT F. LINDEMANN, a citizen of the United States, and residing at Providence, in the county of Providence and State of Rhode Island, have invented a certain new, original, and ornamental Design for Husks for Lighting Fixtures, of which the following is a specification, reference being had to the accompanying drawing, forming part thereof.

Fig. 1 is a perspective view of a husk for lighting fixtures, showing my new design.

Fig. 2 is a side view of the same.

I claim:

The ornamental design for a husk for lighting fixtures as shown.

ROBERT F. LINDEMANN.
